UNITED STATES PATENT OFFICE.

MATTHEW F. ALLEN, OF NASHVILLE, TENNESSEE.

RANGE CONSTRUCTION.

No. 809,766.

Specification of Letters Patent.

Patented Jan. 9, 1906.

Application filed February 27, 1904. Serial No. 195,560.

To all whom it may concern:

Be it known that I, MATTHEW F. ALLEN, a citizen of the United States, and a resident of Nashville, in the county of Davidson and State of Tennessee, have invented new and useful Improvements in Range Constructions, of which the following is a full, clear, and exact description.

This invention relates to certain improvements in the construction of steel metal ranges—*i. e.*, ranges the bodies of which are formed of sheets of steel or other metal.

By means of my improvements the construction of the stove or range is greatly simplified, and yet the strength and durability are increased. Further, I am enabled to add to the range a hot-water reservoir by the expenditure of but a nominal amount of labor and material.

This specification is an exact description of one example of my invention, while the claims define the actual scope thereof.

Reference is to be had to the accompanying drawings, forming a part of this specification, in which similar characters of reference indicate corresponding parts in all the views.

Figure 1 is a sectional perspective view illustrating one corner of the body of the range opposite the reservoir and illustrating the manner of forming the body. Fig. 2 is a detail perspective of one of the corner-irons employed in the formation of the body and reservoir. Fig. 3 is a section on the line 3 3 of Fig. 1. Fig. 4 is a section on the line 4 4 of Fig. 7, showing one of the corner-irons of the reservoir. Fig. 5 is a section on the line 5 5 of Fig. 7, showing one of the junction-irons between the body and reservoir. Fig. 6 is a vertical section showing the reservoir, the fire-box, and the part of the body adjacent to the fire-box. Fig. 7 is a fragmentary perspective view illustrating the reservoir and part of the fire-box and having parts broken away to show certain of the corner and junction irons. Fig. 8 is a fragmentary perspective view of one of the junction-irons looking toward the inside thereof and showing by dotted lines the manner of engaging the sides of the range-body with the iron. Fig. 9 is a perspective view of a portion of the reservoir. Fig. 10 is a detail inverted sectional plan view of one corner of the body and reservoir, showing the parts secured to-

gether; and Fig. 11 is a perspective view of 55 the same, the parts being separated.

The body *a* of the range includes the firebox and has its side walls formed of an integral sheet of metal, preferably steel, bent to produce the corners as indicated at *a'* and 60 having its lower portion formed with corrugations *a*² and an inwardly-extending flange *a*³. This flange is split at each corner of the stove, so that the parts of the flange will lie one over the other, and said parts are riveted 65 or otherwise fastened together, as indicated at *a*⁴. To the flanges *a*³ the bottom proper (not shown) is fastened. This forms an extremely cheap and strong construction, the corrugations and flange resisting strains in 70 all directions and the riveting or fastening together of the sections of the flange, as described, serving, further, to increase the rigidity of the stove against crushing strains. This construction also dispenses with the 75 separate bands heretofore employed at the bottom or base of the body and with the work required to rivet the bands or otherwise connect them with the body.

At its upper edge the body is formed with 80 an integral top rim *a*⁵, produced by an outward and thence diagonally-downward bend, the extreme edge being returned or bent upward and inward to form an interior lip *a*⁶, which not only strengthens the top rim, but 85 improves the appearance thereof. The top rim *a*⁵ being formed integral with the body *a* leaves at each corner of the stove an opening *a*⁷, and in these openings at the end opposite the reservoir, as shown with respect to 90 one corner in Fig. 1, are placed the corner-irons *b*, which, as best shown in Fig. 2, have wings *b*¹ fitting under the top rim *a*⁵ and fastened thereto by bolts *c*. Lugs *b*² of angular cross-sectional form project downward from 95 the corner-irons and are arranged to lie against the outer side of the range at the corners. (See Fig. 3.) The corner-irons *b* are preferably constructed of cast-iron and form not only a continuation of the top rim *a*⁵, but 100 also increase the strength of the stove at the corner where the strain and wear thereon is generally the greatest.

Inside of the stove-body, just below the top rim *a*⁵ thereof, are arranged the sheet-metal (preferably steel) plates *d*, which are securely fastened to the sides of the body by 105 means of bolts *e* and which hold between

them and the body the asbestos or other non-conducting sheets *f*. The upper edges of the steel plates *d* are formed with inwardly-bent flanges *d'*, which serve to carry the cast-iron top *g* of the stove. Figs. 1 and 3 fully illustrate these parts, and they have, therefore, been omitted from Figs. 6 and 7; but in practice the plates *d* extend around the four sides of the body. These plates *d* serve, therefore, the double purpose of strengthening the body of the stove and of supporting the cast-iron top thereof.

At the end of the body of the range adjacent to the reservoir (see Fig. 7) the openings *a'*, before mentioned, are filled by the inner ends of the front and back rims *h'* of the main part of the reservoir *h*, and the junction-irons *i* are fitted to the rims *a'* and *h'* by bolts *k*, thereby securely fastening all of the parts together. The junction-irons *i* have angular flanges *i'* engaging the corners of the body at the reservoir ends, and the adjacent ends of the rims cover the irons, as shown. The sides of the reservoir adjacent to the portions of the back rims *h'*, that fit upon the upper faces of the angle-irons *i*, are notched at *h''*, as best shown in Figs. 9, 10, and 11 so as to receive the flanges of said angle-irons. At its outer side the reservoir has a rim *h''*, and corner-irons *b* are applied to the rims *h'* and *h''* the same as to the rims *a'* on the outer end of the body.

The main part of the reservoir *h* constitutes the outer end and the back and front sides of the reservoir proper, said sides being extended to and suitably fastened against the body *a* of the range. (See Figs. 6 and 7.) A bottom *l* and inner end wall *m* are fastened to the reservoir main part *h*, as best shown in Fig. 6, the wall *m* meeting snugly the end rim *a'* adjacent to the reservoir.

n indicates the fire-box of the stove, and *o* indicates a water-back which is suitably joined to the reservoir-wall *m* and projected into the fire-box, so as to communicate to the reservoir the heat of the latter.

The reservoir is fitted with a cast-iron top *p* and a hinged lid *q*, (shown in full lines in Fig. 6 and dotted lines in Fig. 7,) and, if desired, the front end of the reservoir may be covered with an ornamental panel of cast-iron or the like.

It will be observed that all of the novel features of construction entering into my invention tend to simplify and to strengthen the structure of the stove or range, thus enabling me to produce a durable and efficient stove at a relatively low cost. The reservoir may be omitted, if desired, and in this case all four corners of the stove-body will be constructed as in Fig. 1.

Various changes in the form, proportions, and minor details of my invention may be resorted to at will without departing from the spirit and scope thereof. Hence I con-

sider myself entitled to all such variations as may lie within the intent of my claims.

Having thus described my invention, I claim as new and desire to secure by Letters Patent—

1. A stove, having a body formed of sheet metal, the lower portion of which is provided with an inwardly-extending horizontal flange, said flange being split at the corners of the body so that the parts thereof will overlap one another, said overlapping parts being secured together.

2. A stove, having a body formed of sheet metal, the lower portion or base of which is corrugated and provided with an inturned flange, for the purpose specified, said flange being divided on split at the corners of the body, and the sections of the flange being rigidly fastened one on the other at said corners.

3. A stove having a sheet-metal body with an integral top rim formed by bending the upper edges of the body outward and thence downward, the top rim being divided at the corners of the stove, and a corner-iron fastened in between the sections of the top rim at said corners.

4. A stove, having a sheet-metal body with an integral top rim formed by bending the upper edges of the body outward and thence downward, the top rim being divided at the corners of the stove, and a corner-iron fastened in between the sections of the top rim at said corners, the said corner-iron comprising a main portion lying level with the top rim, and wings projected oppositely under the sections of the top rim.

5. A stove, having a sheet-metal body with an integral top rim formed by bending the upper edges of the body outward and thence downward, the top rim being divided at the corners of the stove, and a corner-iron fastened in between the sections of the top rim at said corners, the said corner-iron comprising a main portion lying level with the top rim and wings projected oppositely under the sections of the top rim, and the corner-iron further having a downwardly-projected leg arranged to lie against the adjacent corner of the stove-body.

6. The combination of a stove-body having a rim, a reservoir having a rim, and a junction-iron fastened to said rims, the junction-iron having projecting members arranged at right angles to each other, and a downwardly-extending angular flange at the junction of said members and engaging a corner of the body.

7. The combination of a stove-body provided with a top rim having openings at the corners, angle-irons secured to two corners of the body and having its members extending under the top rims of said body, and a reservoir having a top rim, the front and back rims of the reservoir extending partly over the angle-irons into contact with the front

and back rims of the body and secured to said angle-irons.

8. The combination with a stove-body including the fire-box, of a reservoir comprising side, end and bottom walls, the side walls being projected beyond the inner end wall and fastened to the body, and a water-back attached to the inner end wall and projected into the fire-box.
9. The combination of a stove-body having a top rim, a reservoir main part constituting front and back sides and an outer end

wall and having a top rim with an opening or break therein, junction-irons fastened to the body and reservoir-rims, and a corner-iron 15 fastened in the break or opening in the reservoir-rim.

In testimony whereof I have signed my name to this specification in the presence of two subscribing witnesses.

MATTHEW F. ALLEN.
